UNITED STATES PATENT OFFICE

2,376,230

SASH VENTILATOR

Earl J. Coffed, Depew, N. Y.

Application September 9, 1944, Serial No. 553,392

1 Claim. (Cl. 98—97)

This invention relates to certain new and useful improvements in ventilators for storm sash and the like.

It has for one of its objects to provide a unitary device or attachment for storm sash which is so designed as to embody therein a combined air deflecting shield and adjustable closure therefor.

Another object of the invention is to provide a no-draft ventilator of this character which is simple, compact and inexpensive in construction, and which can be readily applied to and removed from a storm sash.

Other features of the invention reside in the construction and arrangement of parts herein-after described and particularly pointed out in the appended claim.

In the accompanying drawing:

Figure 1 is a fragmentary perspective view of a storm sash showing my improved ventilator applied thereto. Figure 2 is an enlarged longitudinal section taken substantially in the plane of line 2—2, Figure 1. Figures 3 and 4 are transverse vertical sections taken in the planes of the correspondingly numbered lines in Figure 2.

Similar characters of reference indicate corresponding parts throughout the several views.

Referring now to the drawing, 10 indicates a storm sash of ordinary construction having a ventilating slot or opening 11 in its bottom rail for the admission of outside air.

Applied to the inner side of the bottom rail of the sash about its vent slot 11 is a unitary device or attachment consisting of a combined air-deflecting shield and closure therefor, the latter being manually adjustable to regulate the amount of air to be admitted to the room for ventilation. The deflecting shield consists of a body shaped from sheet metal or the like to provide a ventilating section 12 including an inwardly and upwardly sloping front wall 13 and triangular-shaped end walls 14 which extend around the lower side and ends of the vent slot in the sash, the top of this section being open to admit the air into the room in such a manner as to minimize

drafts. At its bottom and ends the section 12 has marginal flanges 15 and 15a, respectively, which bear flatwise against the inner face of the sash-rail, the end flanges serving as attaching flanges for receiving screws 16 to secure the device to the sash.

The adjustable closure for regulating the amount of air to be delivered into the room through the sash-slot 11 is indicated by the numeral 17 and consists of a flat sheet metal plate applied to the open rear side of the ventilating section 12 of the deflecting shield and pivoted at one end at 18 to the companion end flange 15a of such section to swing vertically. Adjacent its free end this plate has a finger piece 19, which may be punched therefrom or otherwise formed, for facilitating its movement to the adjustable positions desired. By preference, those portions of the shield-body inwardly of its end attaching flanges 15a are offset forwardly, as indicated at 20, to provide spaces or pockets for receiving the end portions of the closure plate 17 and bringing the rear face of such plate flush with the companion faces of the end flanges so that the same is effectually retained between the shield body and the storm sash. This unitary assembly of deflecting shield and adjustable closure is easy to apply and remove or interchange when desired, and it is very effective in controlling room-ventilation with a minimum of drafts.

I claim as my invention:

A device of the character described, comprising a ventilator shield open at its top and inner side, and an adjustable closure member for a ventilator opening pivoted at one end to the inner side of said shield and extending in its closed position across the open inner side thereof, the shield being recessed beyond the ends of its open inner side and terminating at its opposite ends beyond such recesses in attaching flanges, and the end portions of said closure occupying such recesses with its inner face substantially flush with the inner faces of the attaching flanges.

EARL J. COFFED.
